(57) **CLAIM**

An ornamental design for a fiber optic temperature sensor, as
shown and described.

DESCRIPTION

FIG. 1 is a right front perspective view of a fiber optic temperature sensor showing our new design;
FIG. 2 is a front elevational view thereof;
FIG. 3 is a rear elevational view thereof;
FIG. 4 is a left side elevational view thereof;
FIG. 5 is a right side elevational view thereof;
FIG. 6 is a top plan view thereof; and,
FIG. 7 is a bottom plan view thereof.
